UNITED STATES PATENT OFFICE.

WILSON B. WIGLE, OF FULLERTON, CALIFORNIA.

UNDERREAMER.

1,273,708.

Specification of Letters Patent. Patented July 23, 1918.

Application filed February 6, 1917. Serial No. 146,892.

To all whom it may concern:

Be it known that I, WILSON B. WIGLE, a citizen of the Dominion of Canada, residing at Fullerton, in the county of Orange and State of California, have invented new and useful Improvements in Underreamers, of which the following is a specification.

The present invention relates to improvements in underreamers, such as are employed to enlarge well holes to permit the lowering of the casing in the hole following drilling.

The invention relates particularly to the class of underreamers in which the cutters are collapsible so that the tool may be inserted and withdrawn through the casing. For this purpose the cutters are pivotally mounted.

It is an object of this invention to provide a construction whereby the pivotal construction supporting the cutters is relieved from strain when the tool is in use.

It is another object of this invention to provide an underreamer having a body of shell form, which is not mutilated by having cut-out portions. Such construction provides a strong durable body easily remachined.

It is a further object to provide a construction such that the cutters are securely held against turning in the body.

I accomplish these objects by means of the embodiment of my invention illustrated in the accompanying drawings, in which:

Figure 1 is a section through a well, showing a casing therein and my improved underreamer with the cutters expanded.

Fig. 2 is a section similar to Fig. 1, showing the cutters collapsed and within the casing.

Fig. 3 is an axial section through the underreamer.

Fig. 4 is a section as seen on the line 4—4 of Fig. 3.

Fig. 5 is a section as seen on the line 5—5 of Fig. 3.

Fig. 6 is a section as seen on the line 6—6 of Fig. 3.

Referring more particularly to the drawings, 8 indicates a well casing which is disposed within a well hole. Within the casing, as shown in Figs. 1 and 2, is my improved underreamer. The underreamer is comprised of a two-part stock or body consisting of a member 9 adapted to be connected to a stem and a shell 10 which contains the working parts of the underreamer.

Members 9 and 10 are threaded together as indicated in Figs. 1 and 3.

The shell is constructed with a bore which has portions of varying diameter. A tapering portion 11 is formed at the lower end of the shell, and is adapted to receive the shanks of the cutters. A cylindrical portion 12 communicates with the portion 11 through a portion 13 reduced in size, and square in cross section. Portion 13 is of such dimensions as to slidably receive a rod which is later described. At the upper end of the shell is a portion 14 of larger diameter than the portion 12, and communicating therewith. An annular shoulder 15 is formed between the portions 14 and 12. The lower face of the shell is cut to form lugs 16, 17, 18 and 19. These lugs form shoulders against which the cutters abut to prevent rotation of the latter, and also to take the strain due to the tendency of the cutters to collapse when expanded. The upper end of the shell has a threaded stem portion 20 which engages a threaded bore in the member 9, and secures the shell to the member 9. A bore 21 is formed in the member 9, and is in effect a continuation of the portion 14 of the bore in the underreamer body. The surface of the shell is flattened, as indicated at 22, to provide a wrench hold.

Disposed within the bore of the shell is a rod 23 which is square in section throughout the major portion of its length, and cylindrical at the upper end. Threads are provided upon the cylindrical portion, and a nut 24 is mounted thereon. Below the nut and upon the rod is a collar 25. Surrounding the rod, one end abutting the collar and the other end the shoulder 26 formed in the shell, is a spring 27. The collar 25 is of such dimensions that when the rod 23 is protracted its full amount from the shell, collar 25 will rest upon shoulder 15, thereby relieving the spring 27 from further strain, and eliminating any danger of breaking the spring. The rod 23 is provided with a head 28 of T-form. A threaded bore 29 is provided in the T-head so that the head may be engaged and withdrawn for dressing the tool, or for any other convenient purpose. A transverse bore 30 in the shell member 10 is provided for receiving a flat key. When it is desired to remove the cutters, the head is withdrawn so that the upper end of rod 23 is at a point such that the key may be inserted in slot 30. This position is shown by the dotted lines in Fig. 3. The

key is then inserted, being in a position just above the nut on the rod. The head is thus kept in protracted position, so that the cutters may be removed for dressing purposes, 5 or for changing the cutters.

The cutters 31 and 32 are identical in construction and are provided with shanks 33 and 34 which are arranged to conform to the bore portion 11 of the shell. Shoulders 10 35 and 36 are formed on the cutters between the blade portions and the shanks. These shoulders abut the lower face of the shell and form therewith pounding surfaces taking the strain of the pounding action when 15 the underreamer is in operation. The upper ends of the shanks are so arranged that when the cutters are withdrawn from the shell and collapsed, they will rest against the lower face of the shell. Rounded surfaces 20 37 and 38 are formed on the cutters and engage the well casing when the cutters are collapsed, as shown in Fig. 2. Recesses are formed in each cutter to receive the T-head 28 and each cutter is pivotally secured 25 to the T-head by a pin, as indicated by 39 and 40.

The cutters pivot on the pins but place no strain thereon when the reamer is in operation. The pivot pins are also concealed 30 under the reamer body, which keeps them in place and prevents them working out.

The cutters are provided with complementary lugs 41 and 42 which extend into the recess formed between the pair of lugs 16 35 and 17, when the cutters are expanded. The cutters are also constructed with lugs similar to lugs 41 and 42 disposed diametrically opposite thereto, and which extend into the recess formed between lugs 18 and 19. Lugs 40 41 and 42 when disposed in their corresponding recess assist in preventing collapse of the cutters. When a strain comes on the cutters tending to collapse them, the lugs 41 and 42 abut the lugs 16 and 17, and are prevented 45 from moving, and thereby prevent pivoting of the cutters and collapse of the same.

When the reamer is to be inserted in the casing, the cutters are protracted from the 50 shell to the position shown in Fig. 2. As the ends of the shanks reach the bottom of the shell, the inner faces of the cutter blades will abut one another and the cutters will be fully collapsed, the upper ends of the 55 shanks will rest against the bottom face of the shell, the rod 23 will have been protracted against the compression of spring 27 and collar 25 will rest upon shoulder 15. In this condition the underreamer is inserted 60 into the casing, and the rounded portions 37 and 38 of the blades will rest against the wall of the casing, thereby holding the cutters in collapsed position. When the un-

derreamer reaches the end of the casing as shown in Fig. 1, the pressure upon the cutters tending to hold them collapsed is released. The spring 27 tending to retract the rod 23 causes the ends of the shanks to slip from the lower face of the shell toward one another, and the shanks slip within the 70 portion 11 of the bore being drawn therein. The cutters are then fully expanded. Any tendency to collapse the cutters will be resisted by lugs on the cutters bearing against those on the shell assisted by the shanks 75 bearing against the bore of the shell. Any tendency to expand will be resisted by the shanks bearing against one another. The pounding of the underreamer is taken up by the shoulders 35 and 36 resting against the 80 lower face of the shell so that no strain comes upon the pivotal support of the cutters. Any tendency of the cutters to turn in the shell is resisted by the lugs on the cutters bearing against the lugs on the shell. 85

What I claim is:

1. In an underreamer, the combination of a stock having a cavity and recesses in the lower face; a rod slidably mounted in said stock; resilient means tending to retract 90 said rod; cutters pivotally mounted on said rod having shanks disposed to be seated in and filling said cavity when said cutters are expanded, said cutters having shoulders offset therefrom and disposed to engage the 95 lower face of said shell when the cutters are expanded, and a lug on each of said cutters at the contiguous faces thereof so disposed that a pair will be disposed in one of said recesses when the cutters are expanded to 100 prevent further expansion, collapse and rotation of the same.

2. In an underreamer, the combination of a stock having a cavity and recesses in the lower face; a rod slidably mounted in said 105 shell; resilient means tending to retract said rod, said stock having means to relieve said resilient means from further strain when the rod is fully protracted; cutters pivotally mounted on said rod and the shanks disposed to be seated in and filling said cavity when said cutters are expanded, said cutters having shoulders off-set therefrom and disposed to engage the lower face of said shell when the cutters are expanded, thereby providing 115 pounding surfaces, and a lug on each of the cutters at the contiguous faces thereof, so disposed that a pair will be disposed in a recess when the cutters are expanded to prevent collapse, turning and further expansion of the same. 120

In witness that I claim the foregoing I have hereunto subscribed my name this 9th day of January, 1917.

WILSON B. WIGLE.
